[57] CLAIM

The ornamental design for a connector for receptacles, as shown and described.

DESCRIPTION

FIG. 1 is a top front left perspective view of a connector for receptacles embodying our new design;
FIG. 2 is a front elevational view thereof, the rear elevational view being a mirror image;
FIG. 3 is a top plan view thereof;
FIG. 4 is bottom plan view thereof;
FIG. 5 is an enlarged left side elevational view thereof, the right side elevational view being a mirror image; and,
FIG. 6 is a reduced top front left perspective view thereof, the second connector and the receptacles being shown in broken lines for illustrative purposes only.

FIG. 1

FIG. 2

FIG. 3

FIG. 4

FIG. 5

FIG. 6
